Primary Examiner—Antoine D. Davis*(74) Attorney, Agent, or Firm*—Stetina Brunda Garred & Brucker(57) **CLAIM**

The ornamental design for a scan tool, as shown and described.

DESCRIPTION

FIG. 1 is a front view of the invention;

FIG. 2 is a left side view of the invention;

FIG. 3 is a rear view of the invention;

FIG. 4 is a right side view of the invention;

FIG. 5 is a top view of the invention; and,

FIG. 6 is a bottom view of the invention.
